CLAIM

The ornamental design for a pad painter handle as shown and described.

DESCRIPTION

FIG. 1 is a top front perspective view of a first embodiment of a pad painter handle showing our new design; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; FIG. 8 is a rear bottom perspective view thereof; FIG. 9 is a top front perspective view of a second embodiment of a pad painter handle; FIG. 10 is a front view thereof; FIG. 11 is a rear view thereof; FIG. 12 is a right side view thereof; FIG. 13 is a left side view thereof; FIG. 14 is a top view thereof; FIG. 15 is a bottom view thereof; and, FIG. 16 is a rear bottom perspective view thereof. The broken lines in the drawings depict portions of the pad painter handle that form no part of the claimed design.

1 Claim, 16 Drawing Sheets
